UNITED STATES PATENT OFFICE.

EUGENE C. BRULL, OF OAK PARK, ILLINOIS.

FILING-MACHINE.

1,322,873.

Specification of Letters Patent. Patented Nov. 25, 1919.

Application filed October 30, 1917. Serial No. 199,263.

To all whom it may concern:

Be it known that I, EUGENE C. BRULL, a citizen of the United States, and a resident of the village of Oak Park, in the county of 5 Cook and State of Illinois, have invented certain new and useful Improvements in Filing-Machines; and I do hereby declare that the following is a full, clear, and exact description of the same, reference being had 10 to the accompanying drawings, and to the numerals of reference marked thereon, which form a part of this specification.

This invention relates to improvements in filing machines.

15 This invention relates to improvements in filing machines of that class set forth in my prior patent for filing machines, No. 982,791, issued January 31st, 1911. It is the object of this invention to improve and refine the 20 machine and to provide a better machine.

A serious objection in machines as heretofore constructed is that the filings get into the bearings, wearing the same away quickly or spoiling the bearings. It is an object of 25 this invention to provide means which prevents the filings or file dust from getting into the bearings, thereby preventing the destruction of the bearings from this cause.

It is further an object of this invention to 30 provide a novel mechanism for adjusting the work bench and a novel mechanism for changing the throw of the file.

It is finally an object of this invention to 35 provide a filing machine which is improved in every mechanism and adjustment, permitting quick and accurate adjustment and providing a machine which will give maximum service with minimum wear and operating expense.

40 The invention (in a preferred form) is illustrated in the drawings and hereinafter more fully described.

On the drawings:

Figure 1 is a vertical section of a filing 45 machine embodying my invention with the motor in elevation.

Fig. 2 is a fragmentary view of the adjustable work bench and mechanism for adjusting the same.

Fig. 3 is an enlarged fragmentary sectional detail of the mechanism for adjusting the work table.

Fig. 4 is an enlarged sectional detail of the mechanism for adjusting the eccentric drive stud.

Fig. 5 is an enlarged sectional detail taken at right angle with Fig. 4 but longitudinally of the adjusting mechanism.

Fig. 6 is a fragmentary section taken through the lower hood along the file shaft.

As shown in said drawings:

1, indicates a suitable base provided with a stand 2, of suitable shape which at the top is provided with an extension 3, recessed on one side, the upper face of said extension being formed semi-circular, and the bottom of said recess being similarly formed but reversed, said two semi-circular portions being struck from a common center and with the same length radius.

The work table or bench 4, may be of any desired shape but as shown is round and is provided with a downwardly directed circular head 5, which is complementary with the curvature of the recessed extension 3 and fits on the same. A scale 6, is provided on the head 5, by means of which the angle of filing 75 may be very accurately determined.

For the purpose of adjusting said work bench 4, a shaft 7 is journaled in the stand 80 2, at the base of the extension 3, and is held from longitudinal movement by a key 8, engaged in a groove in the shaft. A milled head 9, is provided on the outer end of the shaft and a worm 10, on the inner end of the 85 shaft which meshes with a worm gear segment 11, rigidly secured to the head 5, which is provided with a recess for this purpose.

For the purpose of clamping the table in any adjustment complementary apertures are 90 provided in the extension 3 and head 5, in which is inserted a sleeve provided with an internally threaded axial passage, the threads in opposite ends of the sleeve being reversed. A key or pin 13, is inserted in 95 registering grooves in the sleeve and extension which holds the sleeve from rotation.

Threaded into the inner end of the sleeve

is a bolt 14, having a head 15, thereon which fits in a recess in the extension 3 provided for this purpose. A clamp screw 16, is threaded into the outer end of the sleeve and 5 is provided with a shouldered handle 17, which bears against the clamping collar 18, on the screw shaft which in turn fits into a suitable recess in the circular head 5.

Journalized in suitable sleeve bearings 10 19—20 secured in the base 1, and stand 2, is a file holder or shaft 21, provided with a socket in its upper end in which is engaged the shank 22, of a file 23, which operates through a suitable aperture in the work bench.

15 Rigidly secured to the shaft, or file holder 21, is a hood 24, which is provided with a downwardly extending sleeve 25, fitting over the bearing sleeve 20, and which excludes all filings from said bearing.

20 A hood member 26, is rigidly secured to the stand 2, by means of screws 27. Said hood member 26, flares outwardly beyond the lower bearing 19 and working parts, deflecting all dust and oil drippings from 25 the bearings to drop upon the floor.

Oil holes 28, are provided in the bearing sleeves which are closed by screws 29, by means of which oil may be inserted in the sleeves to lubricate the shaft 21.

30 A drive shaft 30, is journaled in a bearing sleeve 31, in a hub 32, integral with the stand 2, and an oil hole 33, and closure screw 34, is provided therefor. As shown a motor 35, is directly connected to the drive shaft 30, but of course a belt pulley or other drive means may be secured to said shaft.

Integral with or rigidly secured to the inner end of the drive shaft 30, is a circular head 36, provided with a dove tailed groove 40 in which fits a cross head 37, having threaded engagement with an adjusting screw shaft 38, which screw shaft is held from longitudinal movement by a spring pressed pin 39, engaging in a groove in the shaft 38.

45 Integral with said cross head member is a stud 40, which engages in an anti-friction sleeve 41, in a bifurcated clamping head 42, the bifurcations 43—44, of which rigidly clamp the head on the file shaft 21, by means 50 of the clamping screw 45.

The operation is as follows:

The work table 4, may be adjusted to any angle desired to file any bevel or otherwise file the work to be operated on by 55 loosening clamp screw 16, and actuating shaft 7, by means of the milled head 9.

The desired position is readily ascertained by the gage 6, and after the desired adjustment has been effected the table is rigidly clamped in that position by the clamping screw and collar 16 and 18 respectively.

Any desired stroke and speed of the file may be obtained by adjusting screw 38,

which in turn adjusts the cross head 37, to vary the eccentricity of the stud 40, in the 65 head 42, which, of course, varies the stroke and speed of the file.

The hoods 24 and 26, act to deflect the dust, oil drippings and filings off of the bearings and effectually house the bearings so that this deleterious matter cannot enter the bearings and destroy the same.

From the foregoing description of the drawings it is seen that I have produced a filing machine in which the various adjustments may be readily and quickly made and in which the parts are strong and will wear for a long time.

75 The machine as a whole is greatly refined and will give long service at minimum expense.

80 Details of construction may be varied and numerous changes may be made without departing from the scope of the appended claims and I therefore do not desire to limit my application for patent otherwise than necessitated by the prior art.

I claim as my invention:

1. A filing machine, comprising a stand, a work table adjustably secured to the top 90 of said stand, means for adjusting and clamping said table, bearing members, a file shaft in said bearing members, means for reciprocating said shaft, a sleeved hood on the upper end of said shaft fitting over 95 and adapted to protect its upper bearing, and a hood on said stand adapted to protect the means for reciprocating the shaft.

2. A filing machine, comprising a stand, a semi-circular recessed extension thereon, a 100 table, a semi-circular recessed head integral with said table and fitting into said stand extension, means for rotating said head in said extension to adjust the table with respect to the stand, and means for clamping 105 the parts in any adjusted position.

3. A filing machine, comprising a stand, a semi-circular recessed extension thereon, a table, a semi-circular recessed head integral with said table and fitting into said stand 110 extension, a worm gear on said head, a worm shaft on said extension meshing with said gear, a clamp sleeve extending through said head and extension, and a screw having threaded engagement with said sleeve and 115 adapted to clamp said head and extension in any adjusted position.

4. A filing machine, comprising a stand, a semi-circular recessed extension thereon, a table, a semi-circular recessed head integral 120 with said table and fitting into said stand extension, a worm gear on said head, a worm shaft meshing therewith, a clamp sleeve extending through said head and extension, a screw having threaded engagement therewith, a clamping collar on said screw, a file 125

- holder, bearings therefor, hoods for deflecting waste oils and filings from the bearings, and means for reciprocating the file holder.
5. A filing machine, comprising a stand, an adjustable work table secured thereto, a file holder, a head secured thereto, a drive shaft, a head secured to the drive shaft, a stud engaging in a slot in the first named head and adjustably secured to the head on the drive shaft, means for adjusting the stud across the faces of said heads, bearing sleeves for said file holder, a movable
- hood secured to the file holder covering one of said bearings, and a rigid hood secured to the stand covering the heads and other bearing sleeve for the file holder. 15

In testimony whereof I have hereunto subscribed my name in the presence of two subscribing witnesses.

EUGENE C. BRULL.
